UNITED STATES PATENT OFFICE

2,066,355

WATERLESS GASHOLDER

John A. Mason, Baltimore, Md., assignor, by
mesne assignments, to Koppers Company, a
corporation of Delaware

Application October 9, 1931, Serial No. 567,946
Renewed March 7, 1936

7 Claims. (Cl. 48—174)

This invention pertains to gas holders and more particularly to that type known in the art as waterless holders.

Holders of such type are shown in various Letters Patent, among which reference may be made to that granted to Konrad Jagschitz under date of August 13th, 1918, No. 1,275,696.

The present invention has for one of its objects the production of a molder of the waterless type wherein the piston-like closure has associated therewith guiding means which is independent of the shell of the holder and which, by reason of its relation to the closure, prevents the closure from tipping or canting.

A further object of the invention is to provide means, working in conjunction with the guiding means, for insuring a gas-tight seal between said guiding means and the piston-like closure as well as between such closure and the inner wall of the shell.

A still further object of the invention resides in the provision of means whereby if a fluent sealing material be used between the relatively movable parts of the holder such material will be collected centrally of the piston-like closure and distributed therefrom to the sealing means located at the periphery of the piston-like closure. Such material under these conditions may likewise be utilized to effect a seal between the piston-like closure and the fixed guiding means.

A still further object of the invention is to provide a plurality of fixed guides extending vertically within the holder and passing through the piston-like closure element whereby tilting or tipping of the closure element is prevented, enabling one to do away with the guide rollers which work against the inner face of the shell and now commonly employed to stabilize the closure element.

Another object of the invention resides in the provision of means for automatically delivering the fluent sealing medium to a container or tank located upon the piston closure and from which it is delivered to sealing devices employed at the periphery of the holder or both at the periphery and in conjunction with the guiding means.

Another object of the invention resides in the provision of suitable guiding means interposed between the piston-like closure and the vertically disposed fixed guiding elements (one or more) extending upwardly through the holder, whereby the closure will be stabilized against tipping or tilting with reference to said fixed guides or guide.

In the drawings I have sought to show several

embodiments of my invention, it being understood, however, that they are merely indicative of various forms which may be utilized.

Referring to the drawings,

Figure 1 is a vertical sectional view of a waterless gas holder embodying my invention and wherein but a single fixed vertical guide is employed in conjunction with a movable piston-like closure;

Figure 2, a vertical detailed sectional view on an enlarged scale of the central portion of the piston-like closure and the associated fixed guiding element;

Figure 3, a vertical sectional view through the central portion of the piston closure showing a dual sealing means employed in connection with a fixed guiding means;

Figure 4, a transverse horizontal view showing a plurality of fixed guiding elements associated with the piston closure, the latter being broken away; and

Figure 5, a vertical sectional view of a closure element and associated fixed guide and modified forms of sealing means, both at the periphery of the movable piston closure and between said closure and the fixed guiding element.

Referring first to the structure shown in Figures 1 and 2, 1 denotes the body or shell of the holder formed from plates so joined as to present a smooth interior surface. Said shell rests upon a suitable foundation 2 and at the lower portion thereof a gutter 3 is produced by an upstanding element 4.

Near the upper portion of the body of the shell there is provided an outlet, as 5, which preferably opens into an off-take pipe 6, the upper end of which terminates above the roof 7 of the holder. The roof will be provided with one or more louver ventilators, as 8.

Mounted within the shell, and movable up and down therein according to the gas pressure obtaining below the same, is a piston-like closure, designated generally by 9.

At the central portion of the closure 9 there is provided a tank 10, preferably annular in form. Extending upwardly therethrough is a fixed post or column 11, preferably formed of piping and externally finished so as to provide a smooth surface.

Mounted above the tank 10 and secured thereto, is a guiding shoe 12 which makes a relatively close fit with the tubular member or column 11. As will be seen upon reference to Figure 2, the upper and lower edges of the central opening which is formed in the shoe are rounded so that

there can be no binding action between it and the column.

Contracting rings 13 and 14 are seated in grooves formed in the inner face of the shoe 12 and bear directly against the member 11. Extending upwardly from the outwardly extending flange 15 of the shoe is a cylindrical element 16, said element being flanged at its lower and upper ends, as at 17 and 18. The flange 17 is connected with the flange 15 and the flange 18 is connected with the flange 19 of a second guiding shoe 20. The shoe 20 has its inner edges rounded, as is the case with the lower shoe 12, and carries contracting rings 21 and 22 which function with the vertical column or guiding member 11. The space formed by the cylindrical member 16, the shoes 12 and 20, and the column 11 is designed to be filled with a suitable lubricant material, such as grease, tar or the like. It is supplied thereto through a pipe 23 connected with a reservoir 24 in which latter is mounted a piston 25 which is constantly urged downwardly through the action of a weighted lever 26.

As will be seen more particularly upon reference to Figure 1, the closure element 9 is suitably braced by frame-work, designated generally by 27, which latter is in turn connected to the upper portion of the guiding and supporting element formed by the shoes 12 and 20 and the intermediate connecting member 16.

There is thus provided suitable guiding and stabilizing means between the piston-like closure 9 and the guiding column 11 which prevents the tipping or tilting of the closure to such an extent as would open up or render ineffective the sealing means, to be later described, employed between the piston-like closure and the inner wall of the shell.

Sealing medium employed in conjunction with the sealing means at the outer portion of the piston closure is fed to said means from the tank 10 through suitable pipes 28. The sealing liquid may be fed to the tank by any suitable means.

In the instant case there is shown a pipe 29 extending upwardly and beneath the roof 7 and terminating within the hollow column 11. Its down-turned end discharges into a cup 30 supported upon a cross partition 31 secured within the column 11 and just below lateral openings 32 formed therein. The fluid sealing medium is thus conducted to the outer surface of the column 11 and tends, in a measure, to lubricate the same. It is caught as it passes downwardly by a cup 33 mounted upon the upper end of the shoe 20. From the lower portion of this cup there extends a pipe 34 which terminates over or within the tank 10.

At its lower end pipe 29 is connected to the outlet of a pump 35, which latter is driven by an electric motor 36. The inlet of the pump is connected by a pipe 37 to a supply tank 38 which in turn is connected through a pipe 39 with the gutter 3.

Motor 36 is designed to be brought into action when the liquid sealing medium within the tank 10 falls below a given level. Any suitable means for opening and closing the circuit according to the liquid level in the tank 10 may be employed and there is shown, more or less diagrammatically in Figure 1 of the drawings, a means whereby this may be effectuated.

Pivoted to a bracket 40 secured to the piston 9 is a float lever 41 having attached to its outer

end a float 42. A link 43 extends upwardly from the lever 41 and is attached to one end of a lever 44 of the first order. A rope or cable 45 attached to the opposite end of the lever 44 passes upwardly and over suitable pulleys 46, 47 and thence downwardly outside of the shell of the holder. To the lower end of this cable 45 is attached one end of a bar 48 upon which is mounted a mercoid switch 49. To the opposite end of the bar 48 there is secured a cable 50 which passes upwardly over and about pulleys 51 and 52 and thence downwardly within the body of the holder where it is connected to the framing 27 of the piston closure. It will thus be appreciated that as the float rises cable 45 will be drawn downwardly within the holder and upwardly through that portion which is without the holder, tipping the rod 48 and throwing the mercury within the switch 49 away from the circuit terminals therein.

Wires or cables 53 and 54 extend from the terminals just mentioned and are looped, as shown in Figure 1 of the drawings, to permit descent of the piston without placing strain upon the cables. The cables or wires are connected to the motor 36 and one of them includes in its run a source of electrical energy 55. It will thus be seen that as the float falls the mercury within the switch 49 will close the circuit through the cables 53, 54 and thus energize the motor bringing the pump 35 into action and thereby forcing the liquid sealing medium upwardly through pipe 29 from which it is discharged into the column 11 in the manner heretofore set forth.

The liquid sealing medium passes outwardly through the openings 32 over the outer face of the column 11 and into the cup 33. It thus serves to lubricate the outer surface of the guiding and stabilizing column 11 and finally passes into the tank 10 through the pipe 34. The liquid also produces a seal between the column and the contacting guiding means carried by the piston-like closure.

As will be appreciated, any form of seal may be utilized in connection with the outer portion of the piston and the inner face of the holder. In Figure 1 there is shown a trough or channel which surrounds the piston closure. Said channel is denoted by 56 and is in communication with the tank 10 through the pipes 28.

The level of the sealing medium within the trough 56 is maintained by flow from the tank 10 in which latter the liquid is maintained at a fixed or approximately fixed level through the means heretofore described.

The sealing means shown in Figure 1 is comparable to that shown in the patent to Jagschitz No. 1,481,099, to which reference is made. It may be said to comprise a series of rubbing bars 57 urged outwardly against the smooth inner wall 60 of the shell or holder 1 through weighted levers 58. As in the Jagschitz patent, the lower portion of the trough is produced from canvas or the like and is denoted by 59. To prevent the tank from contacting the foundation and to prevent interference between the pipes 28 and the member 4 I preferably provide a plurality of stools, as 60, extending upwardly from the foundation of the structure and designed to contact the piston body when the piston closure is moved downwardly to its full extent. Acting in a similar manner in a series of legs 61 depending from the piston closure 9 and contacting the foundation or base of the structure as the piston comes to rest upon the stools.

5   Outlet 5 and its stack 6; together with the louver ventilator 8 keep the shell above the piston free of any accumulation of gas so that workmen 5 may readily enter the holder above the piston at any time through a trap-door (not shown) in the roof. Furthermore the opening 5 is placed at such a distance below the roof as to provide a free outlet for the gas from the holder when the piston closure is moved upwardly so that it clears 10 said opening. Thus the gas is prevented from forcing the piston-like closure upwardly to such an extent as would force it into contact with the roof structure and the pipe or conduit 29. It will therefore be seen that the opening 5 performs 15 a dual function. It assists in ventilating the holder above the piston,—in case of leakage, and it acts as a safety vent for gas from beneath the piston when the gas pressure is such that the piston would be forced upwardly to too great an extent were it not for the presence of this safety vent.

It will be appreciated that the tank 10 is centrally disposed with reference to the piston-like closure and as a consequence tends to stabilize 25 the same against tipping or tilting. The sealing liquid or medium in the tank adds the needed weight, in part at least, to maintain sufficient pressure upon the gas within the holder to force the same outwardly when occasion requires. The 30 weight of the liquid within the tank does away with the necessity for the employment of weights upon the piston-like closure, at least in holders of moderate size.

Instead of employing one column, as 11, a 35 plurality of columns may be employed for guiding and stabilizing the piston closure. In Figure 4 three such columns are shown and are designated by the numerals 11^a, 11^b, and 11^c. Any form of sealing means may be employed between said 40 columns and the holder. In the instant case they are shown as extending upwardly through a centrally located tank 10^a secured to the piston closure 9. A sealing means, which is a modification in part of the sealing means heretofore described, between the column and the closure is 45 shown in Figure 3 wherein the shoes 12 and 20 are present along with the contracting rings. These shoes are interconnected by a member, as 50 16, spaced away from the column, say 11^a, forming a closed space or chamber for the reception of lubricant which may be forced thereinto through a pipe 62 leading from a grease cup 63. As in the structure heretofore described, the 55 columns are hollow and the cups 33 are present to gather any fluent lubricant that may pass to the outer face thereof. In addition to the sealing means heretofore described in connection with the column, I have shown in Figure 3 the rubbing bar construction coacting with the column, such 60 rubbing bar construction being similar to that above referred to and upon which similar reference numerals are placed with the exponent "a" added thereto. In this instance the tank 10^a serves the dual purpose of a reservoir for feeding 65 lubricant outwardly to the peripheral sealing means of the piston as well as a trough for the sealing mechanism just mentioned in connection with the column.

In Figure 5 a still further modification is shown 70 wherein a column and a portion of a piston closure and holder shell are disclosed. In this instance the column, denoted by 66, passes upwardly through the piston-like closure 9 and the tank 10. The lower guiding shoe, denoted by 67, is of 75 the same form heretofore described and there

extends upwardly therefrom a member 68 spaced from the column and having its upper flanged end attached to a combined guide and sealing element 69. The space formed between the members 67, 68 and the lower end of the member 69 produces a chamber designed to hold a sealing medium which may be supplied thereto in any suitable manner, as through a pipe 70 connected to a pressure cup 71. The upper end of the member 69 is so fashioned as to cooperate with a packing gland 72 so as to force the packing 73, held between the parts 69 and 72, into contact with the column 66 when the gland is drawn downwardly. A cup 74 may be provided upon the upper face of the gland to receive the fluent sealing medium 15 which flows down over the outer face of the column. An off-take pipe 75 extends therefrom to the tank 10 and is comparable to the pipe 34 heretofore described. In addition to the contracting rings, as are shown in Figure 2 and are 20 present in the structure shown in Figure 5, a series of contracting rings 76 may be placed in the element 69 to assist in forming a tight seal between the column and the piston.

As above indicated, any form of sealing means 25 may be employed between the periphery of the piston-like closure and the wall of the shell and in Figure 5 the piston-like closure is shown as provided with an outwardly and downwardly extending flange or lip 77. A series of wedge-shaped 30 members 78, so arranged as to form a complete annular member, rest upon the depending flange or skirt 77 and are forced outwardly into intimate contact with the inner face of the shell or holder through their own weight and the weight of the 35 liquid in the trough above the same. The structure disclosed is comparable to that shown in Figure 5 of the patent to Jagschitz No. 1,275,696 and is merely disclosed as illustrating the breadth of the invention. As above noted, any effective 40 form of seal may be employed between the piston and the inner wall of the holder or shell.

As above pointed out, by having a column, or preferably a plurality of columns, extending upwardly through the holder structure and through 45 the piston-like closure the piston is stabilized against tilting or tipping and yet may move freely up or down as the case may be.

No claim is made herein to a holder having a 50 piston-like closure, guiding means located inwardly of the circumference of the same, a tank for sealing medium carried by the closure and sealing means for sealing said closure with reference to the holder shell and the guiding means, such arrangement being set forth and claimed 55 in my copending application, Serial No. 620,244, filed June 30, 1932, which is a continuation in part of the present case.

Nor is any claim made herein to a holder having a piston-like closure with a guiding column 60 extending upwardly therethrough; sealing means extending around the periphery of the closure; a tank for sealing medium carried by the closure centrally thereof and at such level as to maintain the desired and requisite level of the sealing 65 medium within the sealing means about the periphery of the closure; connections extending from said tank to the peripheral sealing means; and sealing means between the column and a portion of the apparatus directly associated with the 70 closure.

What is claimed is:

1. In a waterless gas holder, the combination 75 of a shell; a piston-like closure therein; means for sealing the closure with reference to the shell;

- a fixed column extending upwardly within the shell and through the closure element; an extended bearing carried by the closure and contacting the column, said bearing including an exteriorly closed chamber open to the column intermediate the upper and lower ends of the bearing; and means for introducing a lubricant into said chamber.
2. In a waterless gas holder, the combination of a shell; a piston-like closure therein; means for sealing the closure with reference to the shell; a fixed column extending upwardly within the shell and through the piston-like closure; an extended bearing between said closure and the column, said bearing comprising a pair of vertically spaced bearing members surrounding the column; and a member connecting said bearing members, said member standing in spaced relation to the column and forming therewith and the spaced bearing members a lubricant retaining chamber.
3. A waterless gas holder as set forth in claim 2, wherein means is provided for feeding lubricant to the lubricant retaining chamber.
4. A waterless gas holder as set forth in claim 2, wherein one of the spaced bearing members at least carries a contracting ring bearing against the column.
5. A waterless gas holder as set forth in claim 2, wherein each of the spaced bearing members carries at least one contracting ring bearing against the column.
6. A waterless gas holder as set forth in claim 2, wherein each of the spaced bearing members carries at least one contracting ring bearing against the column; and force feed lubricating means is connected with the lubricant chamber.
7. In a waterless gas holder, the combination of a shell; a piston-like closure therefor, said closure having a tank located centrally thereof; means for feeding a sealing liquid to said tank; a fixed column extending upwardly through the closure; and means located within the tank and bearing against the column for effecting, in conjunction with the sealing liquid, a gas-tight seal about said column.

JOHN A. MASON.
